UNITED STATES PATENT OFFICE.

ADOLPHUS HENRY FORSTNER, OF PORTLAND, OREGON.

OIL-BURNER.

974,652.

Specification of Letters Patent.

Patented Nov. 1, 1910.

Application filed May 28, 1910. Serial No. 563,852.

To all whom it may concern:

Be it known that I, ADOLPHUS H. FORSTNER, a citizen of the United States, and a resident of Portland, in the county of Multnomah and State of Oregon, have invented a new and Improved Oil-Burner, of which the following is a full, clear, and exact description.

Among the principal objects which the present invention has in view are: to provide a burner wherein is secured a perfect admixture of oil and air; to provide a spiral rotary mixing member for controlling the flow of elements to the burner orifice; and to provide a removable burner fixture adapted to be removed from the supply pipe and arranged to be disassembled for repair or replacement.

One embodiment of the present invention is disclosed in the structure illustrated in the accompanying drawings, in which like characters of reference denote corresponding parts in all the views, and in which—

Figure 1 is a side elevation of a burner fixture shown as applied to the side wall of a furnace, said side wall being shown in section; Fig. 2 is a longitudinal section of the burner fixture and supply pipes connected therewith; Fig. 3 is a side elevation of a bearing plug supporter used in connection with the present invention; Fig. 4 is an end view of the bearing plug shown in Fig. 3, viewed from the bearing end; Fig. 5 is a side view of an eliminating screen; and Fig. 6 is an enlarged view in detail, showing the face of the burner tip.

The invention is specially applicable for use in furnaces, and where it is desired to employ heavy base oils. To assist in the carburetion where oil of the character specified is employed, I have provided a mixing chamber, which in the present construction is formed by a pipe section 7. The pipe section 7 is suitably threaded to fit the head 8 of an angle connection 9, to which an oil supply pipe 10 and an air supply pipe 11 are rigidly attached. The feeding devices for advancing the supply of oil and air employed in connection with this burner are not shown in the drawings. These devices may be of any known character suitable for the purpose for which they are designed.

Within the pipe section 7, and rotatively mounted therein, is a spiral propelling blade 12. The blade 12 is rotatively mounted in said section, and for this purpose is pro-

vided at each end with pivot spindle extensions 13, 13. The spindles 13, 13 are coned at the end, and the cones are seated in inverted conical bearing cups 14 formed in the end of each of the bearing plugs 15, 15. The plugs 15, 15 are similar in construction to cupended set screws, and are provided with square wrench heads 16, 16 whereby they may be rotated to adjust the bearing cups 14 to the spindles 13. Each of the plugs 15 is provided with a jam nut 17, whereby the plugs are held immovable in position after being adjusted.

The plugs 15 are carried in supporters 18, 18, which are cylindrical in shape, having an outside diameter of less than the inside diameter of the pipe section 7. The cylindrical portions of the plugs 18 are provided with lateral wing extensions 19, 19, the outer edges whereof are extended to the outer skin of the section 7, and are there provided with segmental screw threads adapted to align with the screw threads of the ends of the section 7. The ends of the section 7 are slotted longitudinally to receive in holding relation the wing extensions 19. In manufacturing the mixing chamber, the slots are cut in the ends of the section 7 to receive the wing extensions 19, 19 prior to the union thread being formed on the ends of the said section. When the union thread is formed, the wings 19, 19 and supporters 18 are held in position on the section 7 so that the thread which is cut in the pipe section 7 is simultaneously cut in the outer edge of the wings 19, 19. By this arrangement, when the pipe section 7 is screwed into the unions by which it is held in position, the supporters are, at the same time, screwed into and held by the said unions.

The outer end of the pipe section 7 is connected with a tube 20, wherein is supported an eliminating screen 21. The eliminating screen 21 is constructed from perforated material in the form of a disk. The purpose of the screen is to prevent the flashing back from the burner tip. The tube 20 is, at the point of connection with the section 7, of the same diameter as the said section, and is provided with a screw thread similar in pitch and adapted to engage a coupling 22. The coupling 22 is of usual construction as employed in connecting tubes or pipes of similar character to that specified.

At the outer end of the tube 20 is connected a burner fixture 23. The fixture 23

is provided with a solid and enlarged tip 24, which may be constructed from any suitable refractory material. The shank or body of the fixture 23 is threaded, as shown in the drawings, to receive a coupling 25, which is also connected with the threaded end of the tube 20. All the coupling joints, it will be understood, are formed gas-tight by the usual method.

10 The tip 24 is provided at the outer end with a spreading slot 26, usually formed by a saw cut extending across the head of the tip. Communicating with the slot 26, and piercing inwardly the body of the tip, is a 15 small duct 27. At the inner end of the duct 27 the passage thereof is gradually increased to form an inverted cone-shaped passage opening into the duct 27. Extended within the cone-shaped end of the duct 27 20 is a small perforated metal cone 28. The base of the cone 28 is sufficiently extended to touch the entire inner surface of the shank of the fixture 23, and to form a closure therefor, compelling the oil to pass through the 25 cone 28 preliminary to introduction through the duct 27 to the spreading slot 26, where it is burned.

The operation of a system supplied with a burner of the character specified resembles, 30 as to the method of introduction of the air and oil, the systems at present in vogue. When, in the present burner, the oil and air are received from the pipes 10 and 11, they are advanced rapidly past the wings 19, 19 35 of the supporters 18, and impinge upon the spiral plate 12. The plate 12, yielding under the direct thrust of the onrushing air and oil, rotates more or less rapidly as the air pressure is increased or diminished. The 40 oil is drawn from the pipe, and when brought in contact with the rushing air, is, by the air, comminuted. After being comminuted it is carried in the shape of globules into the mixing chamber formed by the 45 pipe section 7, and therein impinges upon

the spiral surface of the plate 12. Upon the plate 12 is thus formed a coating of oil. In the subsequent and continuous action of the burner, the air, in passing through the spiral channel formed by the plate 12, is 50 brought into intimate contact with the oil at all stages of its passage through the mixing chamber. The oil impregnated or oil laden air, after passing from the mixing chamber, enters the tube 20, where any globules of oil or solid matter are arrested by the eliminating screen 21. Beyond the screen 21 the mixed air and oil, is passed to the cone 28, and through the same and the duct 27, to the spreading slot 26 to be 55 burned.

Having thus described my invention, what I claim as new and desire to secure by Letters Patent is:-

1. An oil burner, comprising a supply 60 of pipe; a burner fixture; a mixing chamber interposed between said supply pipe and said burner fixture to form a communicating passage between the same; an elongated spiral member rotatively mounted in said 70 chamber; adjustable bearings for said spiral member; and supports for said bearings having laterally extended wings mounted in slots formed on the ends of said chamber.

2. An oil burner, comprising separate air 75 and oil supplies and connecting ducts therefor; a mixing chamber therefor; a tube connected to said mixing chamber and having an eliminating screen across the passage thereof; a burner fixture having a centrally 80 disposed gas duct; and a metallic cone mounted in said fixture to be heated thereby.

In testimony whereof I have signed this specification in the presence of two subscribing witnesses.

ADOLPHUS HENRY FORSTNER.
